FRICTION-ROTARY BLOTTING DEVICE FOR
DUPLICATING MACHINES

Jack S. McLane, Columbia, S. C.

Application April 8, 1947, Serial No. 740,080

6 Claims. (Cl. 101—416)

1

This invention relates to printing or duplicating machines, such as for producing reproductions of letters, cuts and other matter from a printed form, stencil or wax sheet held upon a drum or cylinder, such as used in duplicating machines of the mimeograph type or the like, and more especially to a device or attachment therefor in the form of a friction-rotary blotting device for such paper duplicating machines, designed to quickly dry or blot the impressions on the paper or printed sheets as delivered from the duplicating machine so as to prevent smearing of the sheet carrying the impression prior to depositing it in a receiving tray.

It is the purpose of this machine to quickly dry and blot the paper carrying the impression, prior to depositing it in the receiving tray and to greatly simplify and expedite the delivery and the drying or blotting of the paper carrying the impression. Paper as it comes from the duplicating machine carries the impression and the ink not having had sufficient time to dry, the result is that the speed of the machine is reduced in order to avoid smearing or otherwise blotting the wet impressions.

It is the purpose of this device to eliminate this difficulty by applying a cylinder having a blotting material surface to the impression as it emerges from the duplicating machine, so that it will be partially dried and reduce the smear as above referred to, and in most instances entirely avoid smearing, and in addition, permit speeding up of the operation of the duplicating machine so that the number of impressions which the duplicating machine can produce, will be greatly increased. The blotting material can be renewed quickly by slipping on a new blotting material surface in the form of a new sleeve on the blotting material roller or cylinder.

In this connection, it might be pointed out that as numerous copies are falling in the receiving tray, the damp surface exposed to the backside of the next impression on the sheet deposited in the receiving tray thereover, is liable to discoloration, smearing and producing an end result which is not neat. Heretofore, a technique known as "slip-sheeting" has been employed on existing machines to prevent smearing and discoloration, but the mechanical aids and operation thereof is relatively complicated especially in the insertion and replacement or setting up thereof, and the present invention is designed to greatly simplify and produce other advantages in facility, over said technique and in the mechanical aids required for the insertion of the

2

required drying sheets, which is entirely eliminated by the present invention.

Another object of the invention is to provide means whereby the blotting material cylinder or roller is prevented from contacting a soft rubber pressure roller positioned therebeneath, when a sheet is not being delivered, so as to keep said soft rubber roller ink free thereby further preventing smearing and discoloration of the impression sheet and to cause the blotting cylinder to engage said soft rubber roller only when the sheet is being delivered. The device is so controlled that when the impression roller of the duplicator which operates beneath the printing or wax stencil form is down, it will automatically operate to lift the blotting cylinder or roller so that it will not engage the soft rubber roller, but will be lowered to receive and advance the impression sheet when the latter is delivered from the duplicating machine, during which time the impression roller of the duplicating machine is raised against the printing sheet or drum as the paper is being fed through the duplicator, thereby pressing the mimeograph surface or sheet between the blotting and soft rubber pressure rollers to dry or blot the impression on the sheet before delivery into the receiving tray.

Another object of the invention is to provide means for facilitating the removal of the drying or blotting roller in order to replace the blotting surface or sleeve thereof and to hold the same out of contact with the soft rubber roller during this operation or at such other times as desired.

A still further object is to provide means for feeding the sheets through when blotting is not necessary, such as due to the absorbent nature of the sheet bearing the impression; to provide means for regulating the degree of pressure of the blotting and drying cylinder against the soft rubber roller and for driving the latter from the duplicating machine, as well as adjustment of the receiving tray for different sized sheets.

Other objects and advantages reside in the details of construction and operation as more fully hereinafter described and claimed, reference being had to the accompanying drawings forming part hereof, wherein like numerals refer to like parts throughout, and in which:

Figure 1 is a side elevation of the blotting device as applied to a duplicating machine;

Figure 2 is a side elevation looking at the opposite side from that shown in Figure 1;

Figure 3 is a top plan view of the device as shown in Figures 1 and 2;

Figure 4 is an enlarged longitudinal sectional view taken on the line 4-4 of Figure 3;

Figure 5 is a transverse vertical sectional view taken on the line 5-5 of Figure 1;

Figure 6 is a fragmentary perspective view showing one of the bearings for the blotting and drying roller or cylinder;

Figure 7 is a perspective view partly broken away and in section showing the blotting or drying sleeve of the blotting or drying roller and the manner of applying the same;

Figure 8 is an enlarged fragmentary sectional view taken on the line 8-8 of Figure 2;

Figure 9 is an enlarged vertical sectional view taken on the line 9-9 of Figure 1, and

Figures 10 and 11 are detail views of the means for holding the blotting or drying roller or cylinder in a raised position.

Referring to the drawings in detail, in which like reference characters designate corresponding parts throughout the several views, a paper duplicating machine 15 is shown, such as a mimeograph or similar device having the usual stand or frame 16 and body or tray 17, which receives the sheets upon which the impression is to be made, for delivery to the drum or cylinder 18 bearing the type, stencil or other form adapted to be reproduced and cooperating with the impression roller 19 journaled therebeneath and which moves into and out of contact with the duplicating roller 18. The drum or roller 18 is suitably journaled in bearings 20 at the sides of the duplicating machine, the shaft 21 of which is provided at one end with a pulley or sprocket wheel 22 driven by a suitable endless drive member, chain or belt 23 in the customary manner. The impression roller 19 is mounted in the ends of levers 24 pivoted at 25 adjacent their opposite ends in connection with the sides or frame of the duplicating machine and adapted to rise and fall so as to present the impression roller against the duplicating roller when an impression is being made by the duplicating machine and the sheet with the impression is ejected by the impression roller, but adapted to move away from the same in a downward direction when no sheet is being passed. This operation is effected in the usual way by cams on the drum 18 engaging beneath rollers of the impression roller levers or arms 24 of the duplicating machine so as to actuate the same in timed relation with the feeding device for the sheets to intermittently feed the same forwardly between the drum and impression roller, at which time the latter moves upwardly and against the stencil or form of the drum to feed the sheets through the machine and at the same time duplicate or print the matter appearing upon the stencil or form of the drum with ink fed thereto in the usual manner.

The drying or blotting device of the present invention embodies an attachment to the delivery end of the duplicating machine, and as in the case of the duplicating machine, comprises a frame 26 having side plates 27 with extensions 28 having holes bolted to the side plates and frame 17 of the duplicating machine 15 as indicated at 29. Frame 26 has a forwarding plate 30 which is disposed adjacent or impinges upon the impression roller 19, usually of soft rubber, of the duplicating machine so as to receive the sheets as delivered with the impression thereon from between the drum 18 and roller 19, between the blotting roller 31 and a soft rubber

pressure roller 32, the former of which is removably journaled in arms 33 of a yoke including a transverse horizontal shaft 34 pivoted through the sides 27 of the frame 26 and the latter of which is fixed to a shaft 35 journaled in the sides 27 beneath the roller 31. The plate 30 is suitably supported in the frame 26 as by means of angle iron supports 36 bolted to the inner faces of the sides 27 and an end plate 37 flanged at its edges and similarly attached to the side plates 27 as indicated at 38, while the plate 30 is detachably connected to the angle members 36 as indicated at 39.

At the delivery side of the drum 31 and the pressure roller 32, an inclined discharge plate 40 is mounted between the sides 27 and supported by a vertical flanged plate or wall 41 which is in turn detachably or otherwise connected to the bottom 42 bolted to the bottom flange of the end plate or wall 37 as at 43 and provided with side flanges 44 bolted to the sides 27 of the frame 26 as indicated at 45 from which depend triangular extensions 46 braced to the sides 27 and bottom 42 by a flanged end plate 47 suitably bolted in position through the flanges as indicated at 48 to the sides 27 and bottom 42 to fit the frame and stand of the duplicating machine as more particularly shown in Figures 1 and 2 of the drawings. The bottom 42 forms the bottom of an extension or receiving tray 49 which receives the printed sheets after the impression is made and the same are blotted in a manner to be hereinafter described. This tray has outwardly flanged sides 50 with the tray open at both ends. A slideable end plate 51 extends upwardly from a bottom portion 52 having depending side flanges 53, slideable in a guideway 54 comprising a substantially U-shaped or flanged plate having out-turned flanges 55 bolted to the bottom 42 as indicated at 56, in which the bottom portion 52 of the adjustable end member 51 slides and is frictionally held by an inverted V-shaped spring 57 secured to the bottom of the guide 54 at one end, as indicated at 58 so as to hold the adjustable end member 51 in adjusted position extending upright at the open discharge end of the tray. The flanges 53 are provided with turned ends 59 forming stops or shoulders to engage the side edges of the sides or flanges of the guideway 54, to prevent displacement of the adjustable upright member 51 when moved outwardly to accommodate sheets of different lengths.

Suitable cams on the drum 18 cooperate with rollers on the impression roller levers or arms 24 of the duplicating machine 15 in the usual manner, to move the impression roller 19 downwardly away from the printing surface of the drum when no sheet is being fed, but to move the impression roller against the drum for the impression as the sheet is fed forwardly between said drum and roller and onto the forwarding plate 30 so as to pass between the blotting or drying roller 31 and the pressure roller 32. The upward movement of the impression roller 19 may be additionally effected by means of springs 60 connected to the levers or arms 24 and having adjustment screws 61 operating through threaded ears 62 on the sides of the frame of the duplicating machine or attachment and connected to the springs to regulate the tension thereof. Both rollers 19 and 32 preferably have coverings of very soft rubber with smooth surfaces. Both rollers constitute feed rollers although primarily, the drum 31 is driven to advance the sheet between

the latter and the impression roller 19, and may be turned manually by means of a crank or from a suitable motor mounted on the frame of the duplicating machine. The shaft of the pressure roller 32 carries a pinion 63 which meshes with a larger pinion 64 fixed to a shaft 65 journaled through the sides of the frame 26 and bearing on an extended end thereof, a sprocket wheel 66 around which an endless drive member or chain 67 is trained in connection with a sprocket wheel 68 fixed to the shaft 21 of the printing or duplicating drum 18 so as to drive the pressure roller 32 from the drum, which as before specified, is suitably driven manually or by motor on the duplicating machine in the usual manner.

The blotting or drying roller 31 has its shaft 69 extending axially through a core 70 over which is a wood or like cylinder 71 bearing a tubular cork or soft covering 72 on which a removable and renewable absorbent or blotter or blotting and drying covering, sheet or sleeve 73 is mounted so as to be renewable and for which the cork covering forms a foundation so as to be relatively soft whereby to conform to and engage all parts of the impression by conformation therewith to insure blotting or drying of the wet ink of the printed sheet by contact with the impression or printed side thereof in passing between the rollers 31 and 32. This is due to the fact that the printed sheet is printed on its upper surface as it passes beneath the drum 18 of the duplicating machine and this surface is therefor presented upwardly against the blotting or drying roller 31 as it passes therebeneath. The roller 32 assists in conformation, drying and blotting by pressing upwardly against the blotting or drying roller, against the bottom face of the sheet. The roller 32 like the impression roller 19, may have the rubber sleeve or covering thereof of soft rubber with a perfectly smooth exterior surface, mounted on a core of wood or other material, as indicated at 73. Thus, the friction which is caused by the rubber covering of the roller 32, causes the paper to pass under the blotting or drying roller 31 and to turn the latter as the roller 32 is driven or activated by the gears which are in turn driven or activated by the sprockets and chain taking its mechanical impulse from the shaft of the rotating duplicating drum.

In order to detachably mount the blotting or drying roller 31, the latter is held in position by nuts or collars 74 at the reduced ends of the shaft or core 70 which are provided with bearing sockets outwardly of end plates 75 held in position by the collars or nuts 74, as indicated at 76 to rotatably engage inwardly pressed spring pins 77 held in sleeves 78 fixed to the free ends of the arms 33 of the yoke supporting the roller 31 and having knurled heads, knobs or nuts 79 on the outer ends of the pins so that they may be pulled outwardly to permit insertion of the roller 31 and engagement of the inner ends of the pins with the sockets 76 by releasing the spring pressed pins, thereby permitting the roller 31 to be removed for renewing the absorbent or blotting and drying surface or sleeve 73 by merely displacing the pins from the sockets so that the roller 31 can be readily removed from its supporting yoke within the sides of the frame 26. Heads or knobs 79 have flat surfaces 80 engaged by the bent ends 81 of springs or strips 82 secured to the outer surfaces of the arms 33 in order to prevent turning of the heads, and thus the pins 77 to which they are fixed so that the roller 31 can turn thereon and move upwardly and downwardly in vertically elongated

slots 83 in the sides 27 of the frame 26 for engaging the impression or ink surface of the sheets as they are delivered between the blotting or drying roller 31 and the pressure roller 32. However, the roller 31 and arms 33 are resiliently held downwardly as by means of springs 84 connected to the arms 33 at their upper ends and rods 85 at their lower ends which extend through studs 86 bolted through the side plates 27 and bear nuts 87 on their lower threaded ends to constitute adjustable tension members for controlling the pressure of the roller 31 exercised against the roller 32.

In order to raise and lower the blotting or drying roller 31 so as to raise it out of contact with the pressure roller 32 when a sheet is not passing and to move it into engagement with the sheet when delivered by the duplicating machine, in timed relation to the entry of the sheet between said rollers and so that the roller 31 will be raised when the impression roller 19 is down and to lower it when the impression roller 19 is raised automatically during the feeding of the paper sheets for the purpose of printing or making an impression thereon and so that the blotting roller will not engage the pressure roller directly so as to keep the same ink free, the following means is provided. Angular levers 88 are fixed or pinned to a shaft 89 through the sides 27 and the short arms thereof toward the duplicator bear steel rollers 90 which impinge or engage upon the bottom of the impression roller levers 24 of the duplicating machine. The outer or long arms of the levers 88 are adjustable in length and each includes an extension section 91 having a pair of slots 92 through which clamping screws 93 engage to turn in threaded apertures 94 in the arm for the purpose of adjusting the length of the long arm. The free end of each arm carries a steel roller 95 which engage beneath the arms 33, so that when the paper sheets are not being ejected by the duplicating machine, the cams on the drum 18 will cause the impression roller 19 to be lowered or moved in spaced relation downwardly beneath the drum, thereby pressing downwardly on the rollers 90 to swing the levers 88 on their pivots and the longer arms upwardly to raise the arms 33 of the yoke and thus lift the rotatable blotting roller from the impression roller 32 whereby the ink from the blotter or absorbent roller will be prevented from being transferred to the pressure roller, thus preventing possible discoloration or smearing of the roller 32 so as to keep it ink free. However, the long arms are normally held downwardly by means of springs 96, the tension of which may be adjusted, said springs being connected to the long arms at the extensions 91 and to the sides 27 of the frame 26 so as to normally hold the rollers 95 out of engagement with the arms 33 and when the impression roller 19 held up against the drum 18 by the cam mechanism or the springs 60 when passing and duplicating or printing a sheet. However, when the impression roller 19 is moved down when a sheet is not passing, that is between the printing operations of the duplicator, the levers 88 are swung to cause the rollers to engage the arms 33 and raise the blotting or drying roller 31 thus preventing smearing or marring of the impression. In other words, when the paper sheets are fed through the duplicator, the impression roller will automatically come up or be raised causing the blotting or drying roller to come down, pressing the

mimeographed surface between the same and the pressure roller 32 to dry or blot the paper. The drying or blotting roller 31 can be readily removed from its mounting assembly at the extremities of the arms 33 of the yoke not only for the purpose of permitting renewal of the blotting sleeve or surface 73, but for use when the nature of the paper is such that it is comparatively absorbent and the ink readily dries without blotting. Suitable bearings 97 are provided for the shaft or pivot axis 34 of the yoke and between the sides 27, said pivot axis has arms 98 fixed thereto as by set screws 99, extending through the arms, which latter extend forwardly under the blotting roller 31 as seen more particularly in Figure 4 of the drawings, with loosely pivoted tapered fingers or leaders 100 pivoted on the ends thereof with freely swinging joints, and made of aluminum alloy or otherwise so as to be relatively light and engage over the discharge plate 40 in angular relation to the arms 98 in the direction of discharge of the paper sheets, printed as described, so that even when the blotting and drying roller has been taken out, the fingers or leaders 100 will continue to guide or lead the paper sheets into the tray 49 without putting the drying or blotting roller back in the machine. These guide assemblies, especially the fingers or leaders of the guides, insure that the paper which has carried the impressions is ejected into the receiving tray with the blotting roller in position or out. However, additional means may be provided for this purpose consisting of a relatively U-shaped wire arm 101 having angularly bent crank ends 102 engageable in any one of a plurality of holes 103 in the sides 27 and having its bight or connecting portion mounting small soft rubber rollers 104 with metal bearings and coil springs 105 frictionally slidable thereon on each side of the rollers to permit adjustment of the positions and spacing of the rollers and act as guides therefor. This device lays in the receiver or receiving tray and when it is desired to pass mimeograph sheets printed as described, through, the sheets will be guided into the tray even though the blotting or drying roller is removed, by swinging the same over against the soft rubber surface of the pressure roller 32 under the normal position of the blotting roller to guide the work through the machine and onto the discharge plate 40 and subsequently into the tray 49.

As means of raising the arms of the yoke supporting the blotting and drying roller 31, to facilitate removal and replacement thereof or to hold the arms 33 elevated when the blotting or drying roller is not in use, as when the guiding device 101 and rollers 104 are being used, at which time spring arms or clips 106 secured to studs or bolts 107 at the sides 27 adjacent the discharge ends thereof, bear on the crank portions 102 of the U-shaped arm 101 to hold the rollers 104 against the pressure roller 32, the following means is provided. A shaft 108 is journaled through the frame 26 at the sides 27 beneath the bottom 42 and beneath the intermediate portions of the arms 33. This shaft bears on its ends, substantially heart-shaped cams or eccentrics 109 engaging steel rollers 110 journaled on the lower ends of slidably bars 111 having each a pair of slots 112 elongated in the lengths of the bars and receiving bolts 113 secured through the side walls 27 to slidably retain the bars against the outer surfaces of said side walls. The upper ends of the

bars are bent outwardly at right angles to provide horizontal angular end portions 114 which engage beneath the arms 33 between the adjustable tension springs 84 and the pivot axis of the yoke bearing said arms. Springs 115 are connected to the ends 114 and to studs 116 extending outwardly from the upper bolts 113 which as before stated, are anchored to the sides 27, so that the springs normally draw the ends 114 and bars 111 downwardly whereby the rollers 110 are caused to constantly engage the cam surfaces of the heart-shaped cams or eccentrics 109. A crank handle 117 is fixed to one end of the shaft 108 for rotating the latter, so that the low portions of the cams when presented to the rollers 110 will permit the springs 115 to lower the bars and ends 114, whereby the drying or blotting roller 31 may swing down with the arms 33 under the tension of the springs 84 while permitting the same to swing upwardly when actuated by the impression roller 19 and arms 88 as previously described. However, by turning the crank handle 117, and presenting the high points of the cams to the rollers 110, the arms 33 and roller 31 may be raised clear of the pressure roller 32 and held in this position to facilitate removal and replacement of the roller 31 specifically, by drawing outwardly on the spring pressed pins 77 at the knobs or heads 79, in removing the absorbent or blotting surface or sleeves 73, in renewing the latter when it becomes absorbed with the ink. The central depression in the cams 109 permits the same to be held against turning with the arms 33 and roller 31 raised so that it is free to turn, instead of pressing on the roller 32, which would interfere with its removal and replacement and the friction and pressure which would have to be counteracted in displacing the pins 77 in order to remove or replace the roller 31.

In the operation of the device, the sheets to be impressed or printed are fed between the duplicating drum 18 and the pressure roller 19 of the duplicating machine with the impression roller 19 lowered. When the forward edge of the sheet enters between said drum and roller, as the drum is rotated, the impression roller 19 is raised against the bottom of the sheet so as to press the same against the stencil or printing form of the drum assisted by the springs 60 or cam mechanism 50 on the drum associated with the rollers of the arms 24 or otherwise, so that the sheet is fed forward to the forwarding plate 30 as it is printed. The sheets with the impressions thereon, are then fed forward between the rollers 31 and 32. However, when the impression roller 19 is lowered, the arms 24 engage the short arms of the levers 88, so as to raise the arms 33 and the blotting or drying roller 31 away from the pressure roller 32 but when the sheet enters between the rollers 31 and 32, the former is lowered by the springs 84 and 96 pulling downwardly on the arms 33 and long arms of the levers 88 with the impression roller 19 raised, thus causing the blotting surface or covering of the roller 31 to be presented to the inked impression of the sheet at the top while being pressed against the roller 32 at the bottom, to quickly and effectively blot and dry the ink on the sheets carrying the impression prior to depositing the same into the receiving tray as previously described. In this way, the difficulty heretofore experienced by the paper sheets coming from the duplicating machine carrying the impression and not having had sufficient time to dry so as to necessitate that the speed of the machine be reduced in order to avoid

smearing or otherwise blotting the wet impressions, is overcome and it is possible to speed up the operation of the duplicating machine by applying the blotting material surface to the impression as it emerges from the duplicating machine, so that it will be partially dried and reduce the possible smearing, discoloration and result in neater work, as well as giving advantages over the existing machines using a technique known as "slip-sheeting" in that the mechanical aids required for the insertion of the required drying sheets is eliminated entirely by the present invention. Obviously, the absorbent or blotting and drying surface or covering for the roller 31 consisting of the sleeve 13, may be readily renewed or replaced when desired, the removal and reapplication of a new sleeve with a clean blotting and drying surface being greatly facilitated by the mounting assembly of the roller as previously described. In this manner, the output of the duplicating machine with work which is not smeared, or discolored, and which is much neater is possible.

While in the foregoing there has been shown and described the preferred embodiment of this invention it is to be understood that minor changes in the details of construction, combination and arrangement of parts may be resorted to without departing from the spirit and scope of the invention as claimed.

What I claim is:

1. A blotting and drying attachment for duplicating machines having a printing drum suitably driven and an impression roller coacting therewith, means coacting between the drum and impression roller to cause raising and lowering of the impression roller to engage the drum and printing surface or to move downwardly away from the same when the sheets are fed forwardly and upwardly against the sheet for impressing the same, comprising levers swingably supporting said impression roller, a blotting and drying roller, a yoke movably supporting said blotting and drying roller to be raised and lowered, a pressure roller beneath the blotting and drying roller, means for driving said pressure roller from the drum, lever actuated means between the levers of the impression roller and the arms of the yoke to raise the blotting and drying roller when the impression roller is down and to permit lowering thereof when the impression roller is engaged with a sheet against the drum during the printing of a sheet, means normally holding the blotting and drying roller toward the pressure roller, means for guiding the sheets from between said latter rollers, a receiving tray for the sheets, and means for holding the blotting and drying roller elevated.

2. A blotting and drying attachment for duplicating machines having a printing drum suitably driven and an impression roller coacting therewith, means coacting between the drum and impression roller to cause raising and lowering of the impression roller to engage the drum and printing surface or to move downwardly away from the same when the sheets are fed forwardly and upwardly against the sheet for impressing the same, comprising levers swingably supporting said impression roller, a blotting and drying roller, a yoke movably supporting said blotting and drying roller to be raised and lowered, a pressure roller beneath the blotting and drying roller, means for driving said pressure roller from the drum, lever actuated means between the levers of the impression roller and the arms of the yoke

to raise the blotting and drying roller when the impression roller is down and to permit lowering thereof when the impression roller is engaged with a sheet against the drum during the printing of a sheet, means normally holding the blotting and drying roller toward the pressure roller, a frame supporting said rollers having a discharge and receiving means for the sheets, means for guiding the sheets when the blotting and drying roller is raised or removed, and means engageable with the arms of the yoke to hold the blotting and drying roller elevated in spaced relation to the pressure roller to prevent contact with the latter except when passing a sheet interposed therebetween so that the pressure roller will run ink free and the sheets will be delivered free of smearing and discoloration, and means for holding said lever actuated means in position to permit lowering of the blotting and drying roller.

3. The combination of claim 1 wherein said lever actuated means includes a pair of substantially L-shaped levers pivoted at their leg junctions to a supporting structure, a first roller carried by the shorter legs of said L-shaped levers engageable with the levers of the impression roller to pivot said L-shaped levers in one direction, a second roller carried by the longer legs of said L-shaped levers engageable with the yoke for raising the latter.

4. The combination of claim 3 wherein said longer legs of said L-shaped levers include slidably adjustable extensions for predetermined positioning of said blotting and drying roller above said pressure roller.

5. A blotting and drying attachment for duplicating machines having a printing drum suitably driven and an impression roller coacting therewith, means coacting between the drum and impression roller to cause raising and lowering of the impression roller to engage the drum and printing surface or to move downwardly away from the same when the sheets are fed forwardly and upwardly against the sheet for impressing the same, comprising levers swingably supporting said impression roller, a blotting and drying roller, a yoke movably supporting said blotting and drying roller to be raised and lowered, a pressure roller beneath the blotting and drying roller, means for driving said pressure roller from the drum, a supporting frame, a pair of rockable members pivoted to said frame, a first bearing element carried by said rockable members engageable with the levers of said impression roller to pivot said rockable members in one direction, a second bearing element carried by said rockable members engageable with the yoke for raising the latter, and means normally holding the blotting and drying roller toward the pressure roller.

6. The combination of claim 5 wherein said rockable members include slidably adjustable extensions for predetermined positioning of said blotting and drying roller above said pressure roller.
